UNITED STATES PATENT OFFICE.

SAMUEL J. BRIGHTON, OF FAIRFIELD, IOWA.

DESIGN FOR A STOCK-IMPLEMENT CUTTER-BLOCK HEAD AND HANDLE-STUB.

SPECIFICATION forming part of Design No. 34,409, dated April 23, 1901.

Application filed February 26, 1901. Serial No. 49,000. Term of patent 14 years.

To all whom it may concern:

Be it known that I, SAMUEL J. BRIGHTON, a citizen of the United States, residing at Fairfield, county of Jefferson, and State of Iowa, have invented and produced a new and original Design for a Stock-Implement Cutter-Block Head and Handle-Stub Relating to Stock-Marking, Antirooting, and Dehorning Devices; and I hereby declare the following to be a full, clear, and exact description thereof, reference being made to the accompanying drawings, forming a part hereof.

In the drawings, Figure 1 is a perspective view of a cutter-block head and handle-stub of my new and original design; Fig. 2, a plan view of the same, and Fig. 3 a view in side elevation of the same.

As shown in the drawings, the leading or material feature of my design consists in a head A, having a pivotal point *a*, a flat knife-opposing surface *b*, and a handle-stub B, offset from the plane of the pivot *a*. The portion of the head at the pivot *a* and adjacent thereto is provided with flat lateral surfaces *a'*. The portion *b* has converging sides *b'*. 20 25

What I claim as new, and desire to secure by Letters Patent, is—

The design for a stock-implement cutter-block head and handle-stub herein shown and described.

SAMUEL J. BRIGHTON.

In presence of—

H. H. BRIGHTON,
E. E. LUCAS.
